G. DUFFING

LUBRICATING DEVICE FOR AXLE BEARINGS

Filed Jan. 11, 1926

UNITED STATES PATENT OFFICE.

GEORG DUFFING, OF HAMBURG, GERMANY.

LUBRICATING DEVICE FOR AXLE BEARINGS.

Application filed January 11, 1926, Serial No. 80,651, and in Germany January 21, 1925.

In mechanical lubricating devices for vehicles, more particularly for the axles of railway vehicles, in which the lubricant conveying means consists in a roller, which is 5 pressed against the axle yieldingly, the arrangement as used hitherto will be found sufficient for normal working, but not for abnormal stresses in the axle bearing. Such an abnormal stressing is caused, for instance 10 in the use of railway goods trucks, by their running, during shunting operations, from the ramps on to brake blocks and are caused to jump owing to the sudden braking. This jumping results in a reduction of the space 15 between the bottom surface of the axle box and the axle, which may go so far as to cause the roller-shaped lubricant conveyor to be deformed between the said surfaces. According to the material used in making the 20 lubricant conveyor, the latter will either break or damage will be done to the axle box or, which is worse, the axle itself will be flattened.

This drawback becomes noticeable with 25 roller-shaped lubricant conveying means, the roller diameter of which is so great that only a small amount of space is left between the roller and the bottom surface of the axle box. In other lubricant conveyors 30 with smaller rollers and chain lubrication there will be no flattening of the rollers, but the chains will get twisted, which also makes it impossible for the arrangement to work satisfactorily.

35 All these drawbacks are overcome by the present invention by the provision, in a lubricating device pressed yieldingly against the axle journal and having a lubricant conveyor rotatable about an axis, of guiding means, which in the case of the lubricant conveyor coming dangerously near the bottom surface of the axle box cause a temporary tilting of the spring loaded lubricant conveyor. In this arrangement, when the 40 axle approaches too closely to the bottom surface of the box, the roller tilts over laterally, so that it cannot be crushed or otherwise damaged. As the lubricant conveyor is oppositely spring loaded, it will return automatically to the operative position, on the dangerous approach of the axle towards the bottom of the box ceasing.

In the accompanying drawing a constructional example of the invention is shown, 45 Fig. 1 being a longitudinal section,

Fig. 2 a plan view of the device and Fig. 3 a longitudinal section, showing how the roller is moved into the inclined position.

On the part *a*, on which the whole device is built up, are provided the supporting 50 brackets *b* and the bent-up contact piece *c*. Reference character *d* indicates the pivoted frame for supporting the frame *e* pivoted at *n* in the frame *d* and in which the conveying roller *f* is journaled. The helical 55 spring *g* which is attached to the parts *b* and *e*, holds the frame *e* firmly against the stop member *h* on the frame *d*, when the parts are in the operative position, so that, when the roller *f* is only slightly moved, the 60 frames *d* and *e* will behave as if they constituted a single part, in which the roller *f* runs and which by means of the spring *g* presses the roller against the axle. Thus the lubricant conveyor is held in the operative position by a spring *g* attached at one 65 end to the lubricant conveyor frame and at the other end to a fixed support *b* and by a stop member *h*.

When the frame *d* is moved to any considerable extent about the pin *h*, the stop member *m* fixed to the frame *e* will strike against the upwardly bent contact member *c* (Fig. 3) causing the spring *g* to be tensioned and the frame *e* to rotate away from the stop member *h* so that the roller will tilt over. After this unusually great approach 85 of the axle to the bottom surface of the axle box has ceased, the pressure on the lubricant conveyor will of course diminish and the 90 said conveyor will return automatically into its operative position, that is the vertical or approximately vertical operative position.

Hence, the tilting of the lubricant conveyor is always only temporary.

95 A counter-poise *p* fixed in the frame *d* serves the purpose of balancing the pivoted frame *d* and also prevents the roller chattering, when the spring *f* is a weak spring.

In the construction example shown the 100 roller *f* is journaled in fixed bearings in the frame *e*, but these bearings may be made yielding if desired, although the provision made by the yielding action of the frame *d* is sufficient by itself for the purpose.

105 Other constructional forms of the invention are possible by modifying the example shown. The feature of the invention does not however consist only in the solution of the problem to render the delivery of lubri-

cant certain, even in abnormal working conditions by the one constructional example shown, but embraces generally the solution of the problem of overcoming the danger to the lubricant conveyors, by providing means for tilting the said conveyor and automatically re-erecting it.

I claim:

1. A lubricating device including a lubricant conveyor, means mounting the lubricant conveyor for rotation about a substantially horizontal axis, spring means normally tending to press the lubricant conveyor against a shaft to be lubricated and permitting said conveyor to be temporarily tilted, said mounting means including a frame rotatably mounting said lubricant conveyor, a rocking frame pivotally supporting the first mentioned frame, a support for the rocking frame, and a support for the 20 rocking frame, said spring means being attached to said support and to the first mentioned frame whereby said spring means simultaneously tends to press the lubricant conveyor against a shaft to be lubricated and holds the rocking frame in operative 25 position.

2. A lubricating device as claimed in claim 1 characterized in that said mounting means includes a frame rotatably mounting said lubricant conveyor, a rocking frame pivotally supporting the first mentioned frame, a support for the rocking frame, and means operating to tilt the first mentioned frame 35 with respect to the rocking frame when the latter is displaced to a predetermined extent.

3. A lubricating device as claimed in claim 1 characterized in that said mounting means includes a frame rotatably mounting said lubricant conveyor, a rocking frame pivotally supporting the first mentioned frame, a support for the rocking frame, said spring means acting to normally retain the lubricant conveyor against a shaft to be lubricated and to hold the rocking frame in operative position, and means operating to tilt the first mentioned frame with respect to the rocking frame when the latter is displaced to a pre-determined extent.

In testimony whereof I hereunto affix my signature.

GEORG DUFFING.
